J. C. BOWMAN.
BOILER TUBE CLEANER.
APPLICATION FILED AUG. 16, 1915.

1,180,230.

Patented Apr. 18, 1916.

UNITED STATES PATENT OFFICE.

JOSEPH C. BOWMAN, OF ROY, UTAH.

BOILER-TUBE CLEANER.

1,180,230.

Specification of Letters Patent. Patented Apr. 18, 1916.

Application filed August 16, 1915. Serial No. 45,671.

To all whom it may concern:

Be it known that I, JOSEPH C. BOWMAN, a citizen of the United States, residing at Roy, in the county of Weber and State of 5 Utah, have invented certain new and useful Improvements in Boiler-Tube Cleaners, of which the following is a specification.

My invention relates to improvements in boiler tube cleaners, and one object of my 10 invention is the provision of a cleaner which will adapt itself to tubes of different diameters.

Another object of my invention is the provision of a boiler tube cleaner, which 15 permits of the easy removal of the blades for the purpose of repair or renewal.

Another object of my invention is the provision of a boiler tube cleaner which will remove the scale in a thorough, rapid and 20 efficient manner.

Another object of my invention is the provision of a boiler tube cleaner of the character and for the purpose described, which will be simple of construction, inexpensive to manufacture and one which will 25 be practical and efficient in every way.

With these objects in view my invention consists of a boiler tube cleaner, embodying novel features of construction and combination 30 of parts for service, substantially as shown, described, and particularly defined by the claim.

Figure 1 represents a side elevation of a boiler tube cleaner constructed in accordance 35 with and embodying my invention. Fig. 2 represents a central sectional view thereof, and Fig. 3 represents a front end elevation thereof.

In the drawings: the letter A, designates 40 the handle, of proper length, having its inner threaded end B; engaging the threaded end C, of the head D, said head having the two flaring compressible limbs E, formed with the slot F, to receive the inner flat ends 45 G, of the blades H.

The blades H, are of curved form to provide the forward cutting edges H', having their flat ends secured by the clamping screws J, passing through the hole K, in the 50 end G of the blades H.

Extending inward from near the middle

of the blades H are the studs L, around which coils the ends of the spring M, which spring forces the two blades apart, thereby causing the cleaner to fit snugly.

In inserting the cleaner in the tube the two blades are drawn together and after being inserted are released and the spring forces the blades outward thus insuring an effective and efficient cleaning of the tube.

It will be noted that I provide a boiler tube cleaner that will be simple, durable, efficient and practical in every respect.

The shape of the blades causes them to properly engage the tubes and cut the scale 65 therefrom with ease and quickness and the connection of the blades with the head and the arrangement of the spring allows the blades to adjust or accommodate themselves to the tubes to insure proper fit and ease of 70 movement. Also the manner of connecting the blades to the flaring limbs permits the blades to be quickly removed and applied, and generally in every respect the device 75 will prove efficient, useful and practical.

It will be noted that the blades have a spring disposed between them and that they have when together a circular cutting edge and terminate in a thin edge which can be easily applied to and removed from the head 80 and that the tapering or thin edge gives a proper amount of resiliency to the blades in the cleaning process. Also that the blades may be quickly applied or removed for sharpening or repair and that the detachable form of the head, handle and blades permit of easy repair or replacement of 85 parts.

I claim:

A boiler tube cleaner having a head with 90 oppositely flaring, slotted, compressible limbs, blades with curved outer ends and inner flat ends engaging in said slotted limbs, means for clamping said inner ends in said limbs, a spring disposed between said blades 95 and a handle connected to said head.

In testimony whereof I affix my signature in the presence of two witnesses.

JOSEPH C. BOWMAN.

Witnesses:

E. F. BRATZ.

MAE RYAN.
